UNITED STATES PATENT OFFICE

162,491

DRESSER OR SIMILAR ARTICLE OF FURNITURE

Maxwell H. Sussman, Kew Gardens, N. Y.

Application June 4, 1949, Serial No. 3,059

Term of patent 3½ years

(CL. D33—6)

To all whom it may concern:

Be it known that I, Maxwell H. Sussman, a citizen of the United States, residing at Kew Gardens, county of Queens, and State of New York, have invented a new, original, and ornamental Design for a Dresser, or Similar Article of Furniture, of which the following is a specification, reference being had to the accompanying drawing, forming part thereof.

In the drawings,

Fig. 1 is a perspective view of a dresser, embodying my design;

Fig. 2 is a front elevational view, to reduced scale, of the dresser shown in Fig. 1;

Fig. 3 is a plan view of the dresser shown in Fig. 2;

Fig. 4 is an end elevational view of the dresser shown in Fig. 2;

Fig. 5 is a detail vertical cross-sectional view, substantially on the line 5—5 of Fig. 2; and

Fig. 6 is a vertical cross-sectional view, substantially on the line 6—6 of Fig. 2.

I claim:

The design for a dresser or similar article of furniture, substantially as shown and described.

MAXWELL H. SUSSMAN.

Certificate of Correction

Design No. 162,491

March 13, 1951

MAXWELL H. SUSSMAN

It is hereby certified that error appears in the printed specification of the above numbered patent requiring correction as follows:

Second column, line 4, after "Fig. 2." insert the following paragraph:

The characteristic features of my design reside in those portions shown in full lines in the drawing.

and that the said Letters Patent should be read as corrected above, so that the same may conform to the record of the case in the Patent Office.

Signed and sealed this 29th day of May, A. D. 1951.
